J. D. MUIR

PHOTOGRAPHIC PRINTING MACHINE

Filed Feb. 14, 1923

UNITED STATES PATENT OFFICE.

JAMES D. MUIR, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINTING MACHINE.

Application filed February 14, 1923. Serial No. 619,008.

To all whom it may concern:

Be it known that I, JAMES D. MUIR, a citizen of the United States of America, residing at Rochester, in the county of Monroe 5 and State of New York, have invented certain new and useful Improvements in Photographic-Printing Machines, of which the following is a full, clear, and exact specification.

This invention relates to photography, and particularly to photographic printing machines. One object of my invention is to provide a means for holding a mask, negative and printing paper in the desired relation during the printing operation. Another object is to provide a means for rapidly changing the mask, negative and printing paper. Another object is to provide a means for making a margin on prints, and to a 15 means for changing the width of the margins. Other objects will appear from the following specification, the novel features being pointed out at the end thereof.

In the drawing, in which like reference 20 characters denote like parts throughout:

Fig. 1 is a perspective view of a printer built in accordance with and illustrating one form of my invention;

Fig. 2 is a fragmentary plan view of a 25 portion of the mask, clamps and margin gauge;

Fig. 3 is a section on line III—III of Fig. 2; and

Fig. 4 is a section on line IV—IV of Fig. 2. 30 The printing machine consists of a cabinet 1 preferably provided with a slanting top 2, in which there is the usual printing panel or glass plate 3. The slanting front 2 is preferably made as a separable part 4 held by 35 hooks 5 in the operative position shown in Fig. 1, and removable for adjusting the printing and pilot lamps which are beneath the panel 3.

A handle 6 is connected to side arms 7, 7 40 which are slotted at 8, 8 to receive pins 9, 9 carried by the sides 10, 10 of platen 11. Each side 10 is carried by links 12' and 12 pivoted at 13 and 14 to a support 15, and pivoted at 16 and 17 to the side of the 45 platen. Thus a movement of the handle 6 causes the platen 11 to move from an inoperative position to an operative one, being at all times parallel to the panel 3.

There is a numbering stamp 18 and a counter 50 55 19 mounted on the top of the platen,

which function as the platen is lowered upon the printing paper P.

Coming now to my invention, I provide masks 20, here shown as being made of thin sheet metal, having the usual cut-out portion 21. The edges 22 and 23 are adapted to lie against metal strips 24 and 25 which form parts of clamps to be hereinafter described. These parts position the masks, and, in addition there is a small aperture 26 60 which slides over a pin 27 to further assist in locating the mask and in holding it in position. Aperture 28 is merely for hanging the masks on a pin when not in use, or they may be held in slot 29 in the front of 70 the cabinet 1.

Strip 25 is spaced from the cabinet except at the ends 30 where screws 31 fasten it in place. This member forms one-half of a hinge, the movable member of which 32 is 75 carried by pintle 33 and spring pressed by a spring 34 toward the printing panel 3. I preferably cut away portions 35 of the edge and bevel the edges remaining at 36 (Fig. 3) to assist in securing firm contact when 80 holding a negative or film F in position. If the film is of the strip variety it may be passed beneath bar 25 (Fig. 4) so that the separate exposures may be printed from 85 without cutting the strip. Plate 24 differs from 25 in being flat on the cabinet top, being held by screws 37, and as the clamping member, hinge, pintle and spring are the same as those above described, the same 90 reference characters are used.

In order to obtain a margin on the print, and to vary the size of the margin, I provide a margin gauge plate 40 on each clamp member. This consists of a flat piece of metal slotted at 41 and having a straight edge 42, being cut away at 43, for clearance of the clamp operating handles 44. These plates may slide about the pins 45 extending through the slots 41, and may be clamped in any desired position by the 100 thumb nuts 46. A scale 47 may be added to the clamp blade to facilitate the proper positioning of the margin gauge.

The operation of my printer is as follows: Selecting a suitable mask 20, the operator 105 slides it against plates 24 and 25 at the same time holding the clamping members raised by depressing handles 44. This, depressing the two handles simultaneously, can be 110 easily done with one hand. When the pin

27 projects through aperture 28 the mask is properly located. The gauge plates 40 can then be adjusted to the desired marking on scales 47 and fastened in position by the 5 thumb nuts 46. A negative F is then placed over mask 20 with the desired portion over the cut-out portion 21, and a portion of the film may be held by one or both clamping members 32, the narrow beveled portions 36 10 pressed by springs 34, insuring a firm grip on that portion of the film held by the clamp. The printing paper P is placed with the edges to the left and bottom contacting with the straight edges 42 of the gauge 15 plates 40. The paper may be manually retained in this position by a corner C until the platen 11 is lowered into operative position by the handle 6.

Having thus described my invention, 20 what I claim as new and desire to secure by Letters Patent is:

1. In a photographic printer, the combination with a hinged negative clamping member, of a margin gauge carried by the 25 hinged member, and a clamping device for retaining the margin gauge in a selected position thereon.

2. In a photographic printer, the combination with a hinged negative holding

clamp, a plurality of pins extending up 30 from the negative holding clamp, a slotted gauge plate, the pins passing through the slots, and means for fastening the gauge plate in a selected position upon the negative holding clamp. 35

3. In a photographic printer, the combination with a clamping member, of a margin gauge mounted thereon, a slidable connection between the margin gauge and the clamping member, a scale mounted on one 40 of the above mentioned parts whereby the relative position of the two parts can be ascertained, and a clamping device for retaining the margin gauge at the desired setting. 45

4. In a photographic printer, the combination with a base plate, of a clamping member hinged thereto, projections extending up from the clamping member, a margin gauge consisting of a metal plate having angularly disposed slots engaging the projections of the clamping member, whereby the gauge may be slid upon the projections to vary the position of the gauge relative to the clamping member. 50 55

Signed at Rochester, New York, this 9th day of February 1923.

JAMES D. MUIR.
